DESIGN FOR A PAPER BURSTER TOY

Otto A. Langos, Chicago, Ill., assignor to Alfred F. Langos, Otto E. Langos, Harold L. Langos, and Matilda R. Langos, Chicago, Ill., partners doing business as Langson Manufacturing Company

Application December 17, 1937, Serial No. 73,691

Term of patent 7 years

To all whom it may concern:

Be it known that I, Otto A. Langos, a citizen of the United States, residing at Chicago, in the county of Cook and State of Illinois, have invented a new, original, and ornamental Design for a Paper Burster Toy, of which the following is a specification, reference being had to the accompanying drawing, forming part thereof, in which:

Fig. 1 is an elevational view of a paper burster toy, showing my new design.

Fig. 2 is a front elevational view thereof rotated 90° about a vertical axis in a clockwise direction; and

Fig. 3 is an elevational view looking at the design from the direction opposite to that in Fig. 1.

I claim:

The ornamental design for a paper burster toy, substantially as shown.

OTTO A. LANGOS.
